UNITED STATES PATENT OFFICE.

MAGGIE ELIZA ZURBRIGG AND GILGAIN A. ZURBRIGG, OF ROSE LAWN,
WISCONSIN.

WHEEL-HOLDER.

SPECIFICATION forming part of Letters Patent No. 612,692, dated October 18, 1898.

Application filed May 20, 1897. Serial No. 637,400. (No model.)

To all whom it may concern:

Be it known that we, MAGGIE ELIZA ZURBRIGG and GILGAIN A. ZURBRIGG, of Rose Lawn, in the county of Shawano and State of Wisconsin, have invented certain new and useful Improvements in Wheel-Holders; and we do hereby declare the following to be a full, clear, and exact description of the invention, such as will enable others skilled in the art to 10 which it appertains to make and use the same.

This invention relates to certain improvements in devices for use by wheelwrights and which are adapted to lift the wheel from the floor and support it while being painted or 15 while a tire is being fitted thereto, the object being to provide a device of this character which shall be simple in construction, easy of operation, and which is not easily gotten out of order.

20 The invention comprises certain novel features of construction and arrangement of parts whereby it is made simpler, cheaper, and otherwise better adapted for the purposes for which it is intended, as will be hereinafter 25 fully described, and specifically defined in the appended claim.

In the accompanying drawings, Figure 1 is a side elevation of our invention, showing the parts in position ready to lift and receive a 30 wheel. Fig. 2 is a vertical central longitudinal section thereof, showing the parts in the position they will assume after the wheel has been raised. Fig. 3 is a vertical central transverse section, and Fig. 4 is a detail sectional 35 view on the line $\alpha\alpha$ of Fig. 3.

Similar reference-numerals indicate corresponding parts in all the figures of the drawings.

1 represents a suitable framework comprising a base 2, having uprights 3 located at each side thereof and provided with openings 4, which are adapted to receive trunnions 5, which form the pivots upon which the supporting-carrier 6 is held. This carrier 6 is 45 preferably cylindrical in form, its upper end being provided with a cavity 7 and a threaded rod 8, the former intended to receive the hub of the wheel and the latter to receive a nut 9, which serves to retain the wheel upon 50 the carrier, as clearly shown, and the lower end of the carrier is provided with a cross-

piece 10, the extremities of which engage with the edges of the uprights, so as to limit the pivotal movement in one direction of the carrier. A spring-catch 10^a is secured to the 55 frame 1 adjacent to the cross-piece 10, with which it engages when the carrier is in its vertical position, and thus serves to hold it in its vertical position while the wheel is being painted or otherwise fixed. The opposite 60 side of the uprights 3 is provided with a cross-piece 11, having a central upper concavity which receives the body of the carrier 6 and supports it in its horizontal position or while the wheel is being placed thereon.

To the outside of one of the trunnions which support the carrier 6 is attached a plate 12, having a plurality of teeth located upon the lower circular edge thereof, which are adapted to engage with a spring-pawl 13, pivotally secured to the uprights 3, and the upper end of this plate extends beyond the upper extremity of the uprights, where it engages with the carrier 6 through the medium of a threaded rod 14, which receives upon its end a suitable 75 nut 15. The end of the trunnion is also threaded to receive a similar nut 16, which serves to retain the plate in place thereon.

The teeth upon the plate 12 and their engagement with the spring-pawl serve to lock 80 the carrier 6 in an inclined position, as shown in dotted lines, so that the mechanic may adjust the parts to bring the wheel into a convenient position to work upon.

It will thus be seen that our invention provides in a simple and inexpensive manner a device which will minimize the labor in lifting or otherwise handling a wheel and which is so arranged that the parts are not liable to get out of order.

Modifications may be made without departing from the essential features of our invention, and we do not wish to be understood as limiting ourselves to the precise details of construction herein shown and described, but 95 reserve the right to make such changes and alterations therein as may fairly fall within its spirit and scope.

Having thus described our invention, what we claim, and desire to secure by Letters Patent, is—

A device for the purposes described, com-

prising a base having uprights arranged thereon, a carrier pivotally secured to the said uprights, said carrier being provided with a cross-piece adapted to engage the edge of the uprights, a spring-catch adapted to engage said cross-piece and lock the carrier in a vertical position, a toothed plate secured to one of the trunnions of the carrier, a spring-pawl pivotally secured to the uprights and adapted to engage the teeth on said plate, a threaded rod adapted to receive the hub of the wheel, and a locking-nut engaging said rod, and

adapted to secure the wheel in place, substantially as described.

In testimony whereof we have signed this 15 specification in the presence of two subscribing witnesses.

MAGGIE ELIZA ZURBRIGG.
